(57) **CLAIM**

The ornamental design for a toddler feeding spoon, as shown and described.

DESCRIPTION

FIG. 1 is a front elevation view of my ornamental design for a toddler feeding spoon;

FIG. 2 is a top elevation view;

FIG. 3 is a rear elevation view;

FIG. 4 is a bottom elevation view;

FIG. 5 is a left side elevation view;

FIG. 6 is a right side elevation view;

FIG. 7 is a perspective view; and,

FIG. 8 is a cross-section view taken along the line A-A of FIG. 2.

The broken lines shown in the drawings are for illustrative purposes only and form no part of the claimed design.
